FEEDING MECHANISM

Lewis Walters, New York, N. Y.

Application February 19, 1947, Serial No. 729,593

2 Claims. (Cl. 74—144)

1

This invention relates to tape dispensing machines and is an improvement over the machine embodied in my prior Patent No. 2,406,418, issued August 27, 1946, for Tape Dispensing Machines.

An object of this invention is to provide an improved means for actuating the feeding mechanism of a machine of this type so as to provide a non-feeding cycle on the initial forward stroke of the operating handle during which cycle the severing mechanism is returned to its normal inoperative position.

Another object of this invention is to provide in a machine of this kind a ratchet pinion carrier which is fixed relative to the drive shaft, the carrier including a ratchet pinion which is rotatably carried by the carrier, and a spring-pressed dog which is swingably carried by the carrier, the dog being engaged by a fixed stop on the return or back stroke of the carrier so that the carrier may have further non-ratcheting movement and the pinion may rotate and move with the carrier on the latter or severing cycle of the drive shaft.

A further object of this invention is to provide in a machine of this kind, an improved means for feeding water to the moistening element and for supporting the water bottle or reservoir.

A further object of this invention is to provide in combination a well, a tape moistening brush, and a bottle supporting bracket fixed to the well, the well and bracket being so constructed and arranged that when the water bottle is in the bracket the weight of the bottle will tend to tilt the well and thereby maintain pressure from below on the tape through the brush.

With the above and other objects in view, my invention consists in the arrangement, combination and details of construction disclosed in the drawings and specification, and then more particularly pointed out in the appended claims.

In the drawings,

Figure 1 is a fragmentary detailed side elevation of a dispensing machine embodying this invention.

Figure 2 is a fragmentary sectional view taken on the line 2—2 of Figure 1.

Figure 3 is a fragmentary enlarged sectional view taken on the line 3—3 of Figure 2.

Figure 4 is a fragmentary plan view of the water well and bottle support.

Figure 5 is a fragmentary vertical section through the moistening means.

Referring to the drawings, the numeral 10 designates generally a housing or frame similar to the housing or frame embodied in my prior patent supra.

2

The housing or frame 10 includes a side wall 11 and a tape feeding shaft 12 extends through the side wall 11 and has secured to the outer end thereof a feeding gear 13. A drive or oscillatable

5 shaft 14 is journaled in the housing 10, extending through the side wall 11 and has loosely mounted thereon a drive gear 15. The drive gear 15 is adapted to be rotated in one direction only by clutch means as will be hereinafter described.

10 The shaft 14 has fixed thereto a pair of elongated plates 16 and 17, the latter having a bushing 18 which may be secured by means of a set screw 19 or other suitable fastening means to the shaft 14. The driving gear 15 is disposed loosely 15 between the two plates 16 and 17 as more clearly shown in Figure 2. The two plates 16 and 17 have journaled therebetween a ratchet or clutching gear 20 which is rotatably mounted on a shaft 21 extending between the plates 16 and 17.

15 In order to provide a means whereby the gear 20 may be clutched to the driving gear 15 upon rotation of the drive shaft 14 in a clockwise direction as viewed in Figure 1, I have provided a clutch gear locking dog 22. The dog 22 is fixed 25 between a pair of plates 23 and 24 which are pivotally mounted on pivot members 25 and 26 respectively, which are secured to the plates 16 and 17 respectively at a point outwardly from the axis of the shaft 14.

20 The dog 22 is adapted to be constantly urged to clutching position by means of a spring 27 which is connected at one end to the outer plate 24 and is connected at the other end to the outer plate or gear carrier 17. A pin 28 is fixed between the outer ends of the two plates 23 and 24 so as to cooperate with the dog 22 in holding these plates in spaced apart relation and loosely with respect to the plates 16 and 17.

25 When the gear carrier which comprises the two plates 16 and 17 is swung in a counterclockwise direction as viewed in Figure 1, in which direction the shaft 14 is rotating on its backward stroke, the dog 22 is adapted to ratchet over the teeth of the gear 20. The dog carrier which com-

30 prises the two plates 23 and 24 is stopped in its ratcheting movement on the return rotation of the carrier comprising plates 16 and 17, by means of stop member or abutment 29 which is fixed to the side wall 11 at a point whereby the pinion 20 and the carrier comprising plates 16 and 17 may have further counterclockwise rotation while the dog 22 is stopped in its swinging movement with respect to the plates 16 and 17.

35 At the time the dog 22 is stopped in its ratcheting movement, the drive shaft 14 is operating on

its tape severing cycle for severing the tape which has been previously fed forwardly on the clockwise rotation of the driving gear 15. When the drive shaft 14 is again rotated clockwise on the feeding cycle or stroke, the gear 20 will loosely roll over the feeding gear 15 during the forward swinging in a clockwise direction of the carrier comprising plates 16 and 17. The two plates 16 and 17 are provided with elongated arcuate slots 30 and 31 respectively, through which the dog 22 is adapted to loosely and movably engage.

After the shaft 14 has been rotated on the forward or feeding stroke thereof for a slight distance, the gear 20 will move up to the stationary dog 22 and this dog will then lock gear 20 with respect to the feeding gear 15. Further clockwise rotation of shaft 14 will cause gear 15 which is now locked to shaft 14 to rotate feeding gear 13. The dog 22 is so mounted with respect to the two gears 15 and 20, that when this dog is in clutching position with respect to gear 20, the dog 22 will be locked between the teeth of the gear 20 and also the teeth of the gear 15, as shown in Figure 1.

By mounting the dog 22 as herein disclosed, this dog will not unduly wear the teeth of the ratchet gear 20 when the shaft 14 is rotating on its backward or idling stroke.

The machine 10 herein disclosed also includes an improved moistening means embodying an upwardly opening rectangular well generally designated as 32. The well 32 includes front and rear walls 33 and 34, and opposite end walls 35 and 36. A longitudinally extending rib 37 is carried by the bottom wall 38 and serves as a partition against which the inner end or back 39 of a tape moistening brush 40 is adapted to engage. The bristles 41 of the brush 40 are adapted to extend upwardly and forwardly, the bristles resting against the front wall 33 of the well 32 and contacting at their upper forward ends with a presser plate 42 of conventional construction. The tape is adapted to be moved between the lower side of the presser plate 42 and the ends of the bristles 41 for moistening the gummed lower side of the tape as it is moved forwardly. The well 32 is adapted to be provided with water which will be disposed at a predetermined level as will be hereinafter described.

The side wall 35 has extending therefrom an L-shaped channel 43 which communicates with the interior of the well 32. A bottle supporting bracket 44 is fixed to the rear wall 45 of the channel 43 and includes a vertically disposed bar 46 which is secured by fastening members 47 to the rear wall 45. An acutely disposed bracket arm 48 extends upwardly and rearwardly from the lower end of the bar 46 and has fixed thereto a transverse arcuate bottle supporting saddle 49. The saddle 49 is formed at its lower end with an inwardly projecting stop member 50 against which the forward lower end of a water bottle 51 is adapted to engage.

The bottle 51 includes a cap 52 having extending therefrom a tube 53 which terminates within the channel 43 and the position of the lower end of the tube 53 with respect to the channel 43 will determine the height of the water within the well 32. The well 32 is adapted to removably engage on a pair of ledges 54 which are carried by the inner sides of the housing 10. The housing 10 is formed with U-shaped cutouts 55 in the side walls thereof, within which the well 32 is adapted to removably engage. Preferably the well 32 loosely rests on the ledges 54 and is adapted to be slightly

tilted due to the weight of the saddle 49 and the bottle 51 so that the bristles 41 will be under constant tension in order that they may frictionally contact the gummed side of the tape and this contact is maintained at all times by the tendency of the bottle 51 and the saddle 49 to tilt the forward end of the well 32 upwardly. In this manner the wearing down of the bristles 41 will be compensated by the upward tilting of the bristles under the weight of the bottle 51 and the saddle 49.

In the use and operation of this device, the oscillatable shaft 14 which is the drive shaft is rotated in a clockwise direction as viewed in Figure 1 to feed the tape forwardly past the moistening brush 40. The tape severing means associated with this feeding means is of such character as explained in my prior patent supra that the cutter is normally disposed across the path of movement of the tape when the drive shaft 14 is rotated reversely to the limit of its counter-clockwise rotation. During the initial forward or clockwise rotation of the shaft 14, the driving gear 15 will be stationary due to the fact that the clutch gear 20 is rotating about the gear 15. When the gear 20 is rotated forwardly and upwardly during its lost motion cycle with respect to gear 15, this gear will then engage the locking dog 22. This dog is held stationary by the swinging carrier comprising the two plates 23 and 24 during the initial clockwise rotation of the shaft 14.

After the dog 22 locks the gear 20 with respect to the gear 15, as shown in Figure 3, the gear 20 and the gear 15 will move as a unit and the gear 15 will be locked to shaft 14. At this time the feeding gear 13 will be rotated by rotation of the driving gear 15. On the return or idling stroke of the shaft 14, the dog 22 will ratchet with respect to the gear 20 so that this gear can freely roll over the periphery of the feeding gear 15 and the latter will be declutched with respect to the shaft 14.

I do not mean to confine myself to the exact details of construction herein disclosed, but claim all variations falling within the purview of the appended claims.

What I claim is:

1. Operating means comprising a frame, a driven shaft journalled in said frame and having a driven gear fixed thereon, an oscillatable driving shaft journalled in said frame, at least one elongated member fixed to said driving shaft, a drive gear disposed adjacent said member and loose on said driving shaft and constantly meshing with said driven gear, a ratchet gear rotatably carried by said elongated member, and constantly meshing with said drive gear, spring-pressed means rockably carried by said elongated member for locking said ratchet gear relative to said drive gear on the forward feeding stroke of said driving shaft, and stationary means mounted on said frame engageable with said spring-pressed means for rendering the latter inoperative on the initial forward stroke of said driving shaft, said spring-pressed means including a second member rockably carried by said first mentioned elongated member and projecting from the outer end of the latter, said first member having a slot therein adjacent the periphery of said drive gear, and a dog fixed to said second member and loosely engaging through said slot.

2. Operating means comprising a frame, a driven shaft journalled in said frame and having a

driven gear fixed thereon, an oscillatable driving shaft journalled in said frame, a pair of plates fixed to said driving shaft, a drive gear between said plates and loose on said driving shaft and constantly meshing with said driven gear, a ratchet gear rotatably carried by said plates and constantly meshing with said drive gear, spring-pressed means rockably carried by said plates for locking said ratchet gear relative to said drive gear on the forward feeding stroke of said driving shaft, and stationary means mounted on said frame engageable with said spring-pressed means for rendering the latter inoperative on the initial forward stroke of said driving shaft, said spring-pressed means including a second pair of plates rockably carried by said first plates and projecting from the outer end of the latter, said first plates each having a slot therein adjacent the periphery of said drive gear, and a dog fixed between said second pair of plates and loosely 20

engaging through said slots, said dog when in ratchet gear locking position being disposed in wedging position between said drive and ratchet gears.
